UNITED STATES PATENT OFFICE

2,649,044

WEB FEED MEANS FOR ROTARY PRINTING MACHINES

Julien Dungler, Basel, Switzerland

Application July 29, 1948, Serial No. 41,315
In France August 11, 1947

4 Claims. (Cl. 101—181)

1

The present invention relates to improvements in machines for printing cloth or like material in several colors. In machines of this type, the impression may become faulty, despite the accurate adjustment i. e. registering of the individual printing devices, owing to the fact that certain fibres of the cloth may undergo deformations, either due to the application of the color, or during an intermediate drying operation, and such deformation may alter the registering of the patterns.

In the printing machine according to the invention, which overcomes the above-mentioned drawback, the cloth to be printed is placed in permanent contact, while it is passing through the machine, over the whole of the treated surface, with a taut support which is very accurately guided so that it cannot undergo any deflection, the cloth being fixed to said support in such a manner that it cannot effect any movement relatively to the support.

According to another feature of the invention, the support is formed by an endless band passing between the printing roller or rollers and the presser roller or rollers.

The invention further contemplates means for tensioning the endless band forming a support, in the longitudinal direction and in the transverse direction.

According to another feature of the invention, the means for guiding the support are adjustable so as to enable the longitudinal tension and the transverse tension of the support to be independently adjusted to the desired value.

According to another feature of the invention, the support may be formed by an endless metal band which is preferably covered with a rubberized fabric adhering firmly to the metal, or with any other suitable material.

According to another feature of the invention, the support may be formed by an endless band of thick cloth which is preferably impregnated with rubber or with any other suitable material.

According to still another feature of the invention, the endless band of thick cloth is laterally guided and tensioned by two endless chains which are preferably mounted on anti-friction bearings and are guided by two rails, the transverse distance between which is adjustable.

According to another feature of the invention, the endless band passes, at the inlet and at the outlet of the machine, over a guiding and/or driving roller, the distance between the axes of these two rollers being adjustable so as to enable the band to be tensioned in the longitudinal direction.

2

According to another feature of the invention, the driving roller or rollers for the endless cloth band and the chains for the lateral guiding and tensioning of said band are driven from the same driving shaft.

According to another feature of the invention, the adhesion of the cloth to its support is favored by a sizing on the unprinted side of the cloth, which is effected either by means of a sizing device located at the inlet of the machine, or by previously applying sizing substance to the support before the cloth is pressed against same.

According to another feature of the invention, the endless band passes, during its return travel, through a cleaning and optionally drying device.

According to another feature of the invention, the peripheral speed of the printing and presser rollers is equal to the speed of translation of the support formed by the endless band.

20 According to another feature of the invention, the endless band travels in a plane which at the same time forms the plane of tangency between the printing and presser rollers.

According to a further feature of the invention, 25 the cloth only rests against the endless band during the forward travel of same.

According to a still further feature of the invention, the endless band may also pass, during its return travel, between printing and presser rollers, in which case a presser roller preferably 30 co-operates with two printing rollers respectively located above and below said presser roller in the same vertical plane which is at the same time at right angles to the planes in which the endless band travels.

Other features and advantages of the invention will become apparent moreover from the ensuing description; reference will be made to the accompanying drawings in which:

Fig. 1 is a diagrammatic elevational view of a printing machine A according to the invention combined with a drier B,

Fig. 1a is an elevational view of one of the printing devices on an enlarged scale, used in connection with the printing machine seen in Figs. 1, 5 and 7,

Fig. 2 is a plan view of the printing machine A and of the drier B of Fig. 1,

Fig. 3 is an end view on the outlet side of the printing machine A of Fig. 1,

Fig. 4 shows, on a larger scale, the lateral tensioning and guiding chains for an endless band of thick cloth.

Fig. 5 is a similar view to that of Fig. 1 of a modification wherein the return travel of the endless band is effected below the printing de-

vices in which the positions of the printing rollers and the presser rollers are reversed relatively to those of Fig. 1.

Fig. 6 is a similar view to that of Fig. 1, provided with intermediate driers between the individual printing devices.

Fig. 7 is a similar view to that of Fig. 6, but with the endless band passing on its return travel above the printing devices.

Fig. 8 is a diagrammatic view of an arrangement wherein the endless band passes on its forward and return travel between printing and presser rollers, and

Fig. 9 is a similar view to that of Fig. 8, of a modification.

In these drawings, A denotes in a general manner a printing machine, the frame 1 of which supports a plurality of individual printing devices 2, 3, 4 of which are adjustable to assume aligned position. Each printing device comprises a presser roller 5, a printing roller 6 in contact with a color trough 6^a, and adjusting means 7 and 8 for registering the individual printing devices in transverse and longitudinal directions, respectively.

The adjusting means of all the individual printing devices may be actuated by means of a pulley 9 driven from means of a belt 10, by a drive shaft 11.

The cloth 12 to be printed, which is contained in a trolley 13, first passes through a bar tensioning device 14, then through selvedge-guides 15, and finally over deflecting rollers 16 and 17.

While it is passing through the machine, the cloth 12 is permanently in contact with a support formed by an endless band 18 the latter passing over the rollers 19 and 20, respectively, located at the inlet and at the outlet of the machine.

The shaft of the roller 20 is journaled in a stationary bearing 21. Said roller is rotated by a pulley 22 which is driven, by means of a belt 23, by the driving shaft 11.

The shaft of the roller 19 is journaled in a slide bearing 24 of a support 24^a. It is thus possible to alter the distance between the guide roller and driving roller 19 and 20 by varying the position of the sliding bearing 24^a in its slide 24, thereby enabling the tension of the endless band 18 to be adjusted.

Before it comes into contact with the support 18, the cloth passes over a pasting roll 26 which dips in a paste trough 21. This device is intended to size the cloth on the unprinted side so as to increase its adhesion to the support 12.

After it comes out of the printing machine A, the printed cloth 12^a passes through a drier B wherein it is dried before being rolled or folded. Said drier may comprise a set of nozzle members 28 and 28^a connected to fans containing blowing boxes 31 and 32 which are respectively supplied with hot air. It should be noted that the space between the sets of nozzle members 28 and 28^a may be so chosen as to enable the cloth to effect a double travel therein, first of all adjacent the nozzle members 28, then adjacent the nozzle members 28^a, which results in an increase in the output.

After having left the drier B, the cloth 12^b passes through a drawing device 33 and then through a folding device 34 and is collected on a trolley 35.

The endless band 18 forming a support for the cloth while said cloth is passing through the printing machine A should be of a certain rigidity

while being of sufficient flexibility to enable it to pass over the guiding and driving rollers 19 and 20. Said endless band may be formed by a metal band which is preferably covered with a rubberized fabric adhering firmly to the metal, or with any other suitable material capable of increasing the adhesion of the cloth to the support thus formed.

The endless band may also be made of a thick cloth which is preferably impregnated with rubber or with another material mainly comprising synthetic resin. In order to ensure the satisfactory usefulness of the cloth supporting band, the same is laterally tensioned by means of the arrangement shown in Fig. 4. The side edges of the endless band 18-18^a are pressed between jaws 36 which are secured to an endless chain 37. Said chain is guided by vertical rollers 38 and horizontal rollers 39, respectively, rolling on lower and upper guide rails 41 and 40. The transverse distance between the two upper rails 40, as well as that between the two lower rails 41 is adjustable, which enables the transverse tension of the endless band to be adjusted, the longitudinal tension of same being regulated and predetermined by the adjustment of the distance between the shafts of the guiding and driving rollers 19 and 20. In each pair of rails 40-40 and 41-41, one of the rails can be moved away from or closer to the other, for example in the manner shown in Fig. 4. The movable rail 40 is provided with a projection or extension 51 forming a nut or a screw-threaded shaft 52 on which is fixed a worm wheel 53 actuated by a worm shaft 54. The lower rail 41 co-operates with similar members 51' and 54'. In order to ensure the same distance between the upper rails and the lower rails, a transmission by means of pulleys 55-56 and a belt 57 makes the adjustments dependent upon one another.

The endless chains 37 are driven by sprocket wheels 42 mounted on the same shaft 20^a as the driving roller 20 while the guide chain sprockets 43 are located on the shaft 19^a of the guide roller 19. In this manner an absolute synchronism is obtained between the drive of the endless band 18-18^a and its lateral tension and guide chains 37.

The foregoing device operates as follows: the cloth 12, which is fed through the tensioning device 14, the selvedge-guides 15 and the deflecting rollers 16 and 17, is pasted on its reverse face by the pasting roll 26 before coming into contact with the endless band 18. In the machine, the cloth 12 adhering firmly to the endless band 18 passes successively through the individual printing devices 4, 3 and 2, i. e. between the printing roller 6 and the presser roller 5 of said devices.

In this manner, all the fibres of the cloth retain their relative position throughout the entire travel through the machine, so as to guarantee a correct registering of the individual patterns.

It should be noted that the endless band 18, with the cloth 12 adhering thereto, travels in a plane which at the same time forms the plane of tangency between the printing and presser rollers 6 and 5 respectively, of the individual printing devices 4, 3 and 2.

The printed cloth 12^a comes out of the machine and passes into the drier B by means of deflecting rollers 16. The first portion of the travel of the printed cloth, after it has come out of the machine, is so arranged that the operator can immediately ascertain the quality of the impression. The necessary corrections of the adjust-

ment, i. e. registry, which are noticed can be effected by means of push-buttons 23^a controlling the adjusting devices 7 and 8 of the individual printing devices 2, 3 and 4.

During its return travel 18^a, the endless band is cleaned and optionally dried by the device 25 before being used again as a support for the cloth to be printed, after passing over the guide roller 19.

The arrangement shown in Fig. 1, wherein the presser rollers 5 are arranged above the printing rollers 6, is particularly suitable for printing by means of engraved rollers. This type of printing requires a fairly heavy pressure which can be readily obtained by arranging a presser roller of suitable weight above the engraved printing roller, and using hydraulic, mechanical, or electromagnetic pressure means. Furthermore, the lower position of the printing roller 6 enables the supply of color for same to be readily effected by simply making it dip in a color trough 6^a.

Instead of engraved printing rollers, it is also possible to use perforated printing rollers in which the color is supplied from inside, enabling an imitation of the so-called film printing to be obtained. This kind of printing requires a substantially lighter pressure than printing by means of engraved cylinders. In this case, it is preferable to reverse the position of the printing and the presser rollers, so as to arrange the presser rollers below the printing rollers.

Fig. 5 shows a machine of this type. As in the machine according to Fig. 1, the cloth 12 which leaves trolley 13 passes through the tensioning device 14, the selvedge-guides 15 and the pasting roll 26 and is pressed against the endless band 18. But contrary to the arrangement of Fig. 1, the position of the printing and the presser rollers is reversed in the printing devices 4, 3, 2 so that the printing rollers 6 are located above the band 18 and the cloth 12 pressed against same, while the presser rollers 5 are arranged below the endless band 18. Owing to the fact that the printing rollers 6 occupy the upper position, their supply of color is effected by a special feed device 44 instead of being effected by dipping as in the machine of Fig. 1.

The arrangement of Fig. 5 furthermore differs from that of Fig. 1 by the fact that the return 18^a of the endless band 18 is effected below the individual printing devices 2, 3, 4. Consequently, the cleaning device 25 is also arranged at the lower part of the machine.

The operation of the arrangement shown in Fig. 5 is identical to that explained with reference to Fig. 1.

Fig. 6 shows a machine which differs from that of Fig. 5 in that individual driers 45 are provided after each individual printing device 4, 3, 2, since the drying of each color immediately after it has been printed has the advantage of preventing smearing when another color is consecutively printed and of retaining a greater brilliance of the color thus fixed. Furthermore, the cloth is fed under similar conditions of dryness to each individual printing device. This method enables the supply of color to be increased and thereby facilitates film printing, and also printing that imitates film printing, obtained by means of an engraved cylinder.

The driers 45 may be of any suitable type, either with blowing nozzle members similar to those of the drier B of Fig. 1, or with electric

or gas lamps, or operating by means of infrared or other radiations.

After having left the machine of Fig. 6, the printed cloth may further pass through a drier of the B type of Fig. 1.

It should be noted that in the machine of Fig. 6, the printing rollers also occupy the upper position.

Fig. 7 shows a modification which is also provided with intermediate driers, but which differs from the machine of Fig. 6 in that the printing rollers 6 occupy the lower position as in the embodiment of Fig. 1.

Consequently, the intermediate drying devices 15 46 which are located after each individual printing device 4, 3, 2 are reversed relatively to those of Fig. 6; furthermore the return of the endless band 18 is effected above the printing devices.

The operation of the machine according to Fig. 7 is identical to that of the previous embodiments.

Fig. 8 shows diagrammatically an arrangement of the endless band 18 wherein said band passes, both during its forward travel and its return travel, over rollers 19, 20 and between the printing rollers 6 and the presser rollers 5 of the individual printing devices 2, 3, 4, 2^a, 3^a, 4^a, schematically indicated thereby enabling the number of colors successively printed to be increased without increasing the size of the machine.

Fig. 9 shows schematically a modification of the arrangement of Fig. 8, wherein one and the same presser roller 48 co-operates with an upper printing roller 49 and a lower printing roller 50, the endless band 18 and the cloth 12 resting on same passing during their forward travel between the presser roller 48 and the lower printing roller 50, and during their return travel between the same presser roller 48 and the upper printing roller 49.

The diameters of the presser rollers 48 of the guide rollers and driving rollers, 19 and 20 respectively, of the endless band 18 may be equal or different.

Of course, the embodiments hereinbefore described and illustrated in the drawings are only given by way of non-limitative examples, and it is possible to alter in any suitable manner the shape, the nature, the arrangement and the mounting of their elements, without exceeding the scope of the invention.

Thus, the guiding of the cloth to be printed may be effected in a different manner to the one illustrated, for example by replacing the tensioning device by an equalizing tenter. Furthermore, the individual printing devices and also the intermediate driers and the drier B may be of any suitable type.

Owing to the arrangement of the machine according to the invention, it is possible to obtain:

1. A perfect disposition of the cloth on the support formed by the endless band 18.
2. An absolute rigidity and accuracy of movement of said support owing to the means enabling the support to be tensioned at will in the longitudinal, as well as in transverse directions of the printing devices relative to the cloth or other sheet material.
3. An easy and permanent registry.
4. The elimination of the usual doubler.
5. A great simplification of operation and adjustment of the support.
6. A considerable increase in output, particu-

larly in the type of printing imitating the film printing.

Having thus described the invention, what is claimed as new and desired to be secured by Letters Patent, is:

1. A machine for continuously printing cloth or other sheet material, comprising in combination a plurality of printing devices, an endless support in the form of a band travelling through said devices, means for guiding said support along its travel to prevent deflection thereof, means on said support fixing said cloth to said support in such a manner that it is substantially prevented in longitudinal as well as in transverse directions of its travel from displacement relative to said support, respective means adapted to tension said endless support in longitudinal and transverse directions thereof and independently of its travel, said means for tensioning said support in transverse direction thereof including gripping means for engaging the lateral edges of said band, chain means connected to said gripping means, and rail means supporting said chain means and arranged for displacement and adjustment along a path extending substantially angular to the direction of the travel of said band.

2. A printing machine according to claim 1 in which said means for guiding said support include sprocket wheels for engagement with said chain means.

3. A printing machine according to claim 1, in which said rail means include extension means, and means engaging said extension means for displacing the latter together with said rail means along said path.

4. In a machine for continuously printing

cloth and like sheet material, the combination of an elongated endless band for supporting said cloth to be printed and adapted for movement in longitudinal direction of said band, means joining said cloth to said band, means for gripping said band at lateral edges thereof and for guiding the band during its movement, means operatively connected to said gripping means and guide means and adapted to displace the latter for tensioning said band in a direction transverse of its movement, spaced apart and adjustably supported roller means adapted to tension said band in longitudinal direction, means positioned on the axes and laterally of said roller means, respectively, and engaging said guide means for moving said band.

JULIEN DÜNGLER.
